UNITED STATES PATENT OFFICE.

ISIDOR OLIVER, OF NEW YORK, N. Y.

DESIGN FOR A GLOVE.

No. 39,685.

Specification for Design.

Patented Dec. 8, 1908.

Application filed May 15, 1908. Serial No. 433,142. Term of patent 3½ years.

To all whom it may concern:

Be it known that I, ISIDOR OLIVER, a subject of the Czar of Russia, residing at the city of New York, borough of Manhattan, in the county and State of New York, have invented a new, original, and ornamental Design for Gloves, of which the following is a specification, reference being had to the accompanying drawings, forming part thereof, in which—

A glove formed in accordance with the design consists of a hand portion A, and a gauntlet portion B. The gauntlet portion is split from the junction of the hand portion therewith to its free end, on the side adjacent to the little finger as shown at C, and the sides of the split are provided with snap fasteners D. The wrist portion is also split as at E, from the beginning of the palm of the hand portion upwardly, and the sides of the split are provided with buttons and button holes F.

I claim:

The ornamental design for a glove as shown and described.

ISIDOR OLIVER.
